APPARATUS FOR LIQUID TREATMENT OF FABRIC AND THE LIKE

August Brunner and Giulio Veronesi, Milan-Precotto, Italy, assignors to Mezzera Societa per Azioni, Milan-Precotto, Italy

Application February 24, 1953, Serial No. 338,502

Claims priority, application Italy March 31, 1952

8 Claims. (Cl. 68—176)

This invention relates to a machine for the ultra-rapid washing of fabrics of all kinds and of any length.

The advantages obtainable by the use of our new machine are effective penetration of the bath into the fabric and efficient vibration of the fabric to effect rapid elimination of undesirable particles and to improve washing efficiency. It has not been possible heretofore to attain very high speeds in fabric treating machines, i. e. fabric speeds exceeding 100 meters/min. on account of the tendency of the fabric to become entangled frequently.

In certain prior machines attempts have been made to reach high speeds by causing a fabric rope to move over cylinders provided with suitable resilient devices, in order partly to eliminate tension. The machine according to this invention operates with the fabric fully free in the bath, any entanglement between the moving fabric windings being eliminated by adopting special curved surfaces and by guiding the fabric by means of oscillating combs and small guide clearances, whereby the available bath volume is utilised to a high degree never attained heretofore.

The machine according to this invention is suitable for washing as well as for any other treatment, such as purging, bleaching or dyeing.

The machine consists primarily of two counter-rotating drums with parallel axes lying over two suitably shaped vats, in which the fabric in an endless web formed by successive windings, is alternately submitted to the action of the bath and to the surrounding air.

The drums rotate in a direction to cause the fabric to fall towards the inside of the vats and to rise towards the outside.

The fabric is introduced into the first vat by means of a liquid spray funnel, each of the vats being provided at one end with a counter chute. The chute on the first vat leads the fabric to the second vat after it has travelled over the entire length of the first vat.

The counter chute of the second vat is utilized for returning the fabric to the first vat when treatment requires a closed cycle of movement of the fabric.

When continuous operation is desired, the fabric issuing from the second vat can be conveyed to other machines.

According to this invention the two vats, which may contain two different liquids, for instance a purging and a washing liquid, are of a form such as to require a limited quantity of liquid and to avoid knotting and entanglement of the fabric windings.

Further features and advantages of this invention will be understood from the following description taken with the accompanying drawings which show diagrammatically, by way of example only, an embodiment of this invention.

Figure 1 is a sectional view of the machine on a plane perpendicular to the axes of the two drums,

Figure 2 is a plan view of Figure 1, and

2

Figure 3 is a detail view on an enlarged scale of the device for adjusting the bath level.

1 and 2 denote two parallel cylindrical drums rotating in the directions indicated by the arrows.

5 Each drum is provided with longitudinal ribs 3, which may be substantially triangular in section. Alternatively, the ribs may be of semi-circular section or other upwardly tapered form.

10 Two vats 4 and 5 are arranged beneath the drums. The inner ends of the vats facing each other are provided with two inclined walls or chutes 4a, 5a for feeding the fabric.

The walls 4b, 5b of each vat into which the chutes 4a and 5a merge, is downwardly inclined and terminates with a short nearly horizontal section 4c, 5c connected with a vertical end portion 4d, 5d.

An opening 6 is formed in each vertical portion and communicates throughout the vat length with a chamber 8. A tube 9 is rotatable in this chamber, said tube being formed with an opening 100 directed along a generatrix and provided at one end with a discharge conduit 7. The tube 9 can be rotated about its axis, thereby adjusting the bath level.

20 Each vat is further provided with heating means 10, for instance in the form of steam or superheated water coils arranged to facilitate transmission of heat, though protecting the fabric in the bath against local superheating or steam bubbles.

25 The two chutes 4a, 5a extend at the top into a receptacle 11, subdivided into two portions by a partition 12. Perforated tubes 13a, 13b are arranged in each portion of the receptacle for supplying liquid to the vats 4, 5, along the chutes 4a, 5a, respectively. For instance, the tube 13a supplies purging liquid to the vat 4 and tube 35 13b supplies washing liquid to the vat 5.

The fabric T is fed to one end of the vat 4 by a feed cylinder 14 and is introduced into the vat through a liquid spray funnel 15. The fabric is carried along by the drum 1 and travels over the latter in successive loose turns over its entire length.

30 On reaching the opposite end of the drum 1 the fabric passes over a counter chute 16 on the first vat into the second vat 5 and travels through the entire length thereof by the action of the drum 2 in successive loops in a direction opposite to its direction of movement on the drum 1.

35 On reaching the opposite end of the drum 2 the fabric may resume by the action of a counter chute on the second vat its initial path and thus effect a closed cycle of movement.

40 When continuous operation is desired, the fabric is drawn by a cylinder 18 and conveyed to other machines (not shown).

45 The fabric is guided on its travel over the drums 1 and 2 by oscillating combs 19 provided with devices (not shown) for automatically stopping the machine if the fabric becomes accumulated or entangled.

50 The above described construction of the vats employs a reduced quantity of both liquid and avoids any knotting or entanglement of the fabric, whereby very high rates of feed, even as high as 180 meters/minute may be reached.

55 The fabric carries along with it large quantities of liquid which considerably increase the washing efficiency in the vertical portions of the path of travel of the fabric.

60 The successive ribs 3 on the drums 1 and 2 are spaced with respect to their height and in relation to the diameter of the drums in such manner that the fabric becomes, disposed in polygonal turns, nearly tangential to the inscribed circle which is the section of the drum. Under

these conditions, the fabric is thrown, between the various ribs, against the cylindrical wall in a resilient manner by virtue of the air cushions between the ribs and polygonal faces, whereby the liquid carried along by the fabric is sprayed in every direction, the penetration of the liquid is considerably accelerated for dyeing purposes and elimination of impurities in the washing is improved. The following proportions may be given by way of example. In a drum of 1000 millimeters diameter, six ribs 50 millimeters high are employed.

What we claim is:

1. In a machine for washing, purging, bleaching, dyeing and like liquid treatment of fabric in rope form, at least one unit comprising a vat for containing a liquid, a rotatably-mounted cylindrical reel disposed above said vat in spaced relationship thereto, means for rotating the drum to continuously carry fabric over it and through the liquid in the vat, while said fabric follows a helical path passing over the reel and forms loops freely depending from the latter and having their lower portions immersed in the liquid contained in the vat, said reel having the form of a cylindrical drum with a horizontal axis and of circular cross section, and a plurality of axially-extending peripheral ribs, the height and angular displacement of said ribs being such that any plane passing through the free edges of two adjacent ribs intersects the cylindrical body of the drum, means for introducing the fabric to be treated from a point above said drum downwardly into the vat at one side of said drum so that said fabric will move upwardly onto said drum at the other side of said drum, said vat having one sloping longitudinal side wall having a sloping plate forming an upper extension of said side wall and a substantially horizontal bottom, said side wall merging downwardly with said substantially horizontal bottom of the vat and upwardly with said sloping plate, said drum being positioned with respect to said vat to cause the fabric to be withdrawn from the bath contained in the vat onto the drum in a substantially vertical path, and said means for introducing the fabric into the vat being positioned to cause the fabric to be fed downwardly onto said sloping plate, means for wetting continuously said sloping plate with a stream of liquid and means for maintaining constant the liquid level in the vat.

2. Machine for washing, purging, bleaching, dyeing and like liquid treatment of webs of fabric comprising in combination, a pair of vats for containing liquid, said vats being parallel to each other and symmetrically disposed with respect to the middle plane of the machine, each of said vats being of rectangular shape in plan view, an outer side wall, a substantially horizontal bottom and a sloping longitudinal side wall rising towards the middle plane of the machine, and a sloping plate merging with the upper edge of said side wall and protruding upwardly towards said middle plane, means for feeding a liquid into each vat and means for discharging and varying the level of said liquid in each vat, a first cylindrical drum and a second cylindrical drum each disposed over one of said vats and having horizontal axes disposed parallel and symmetrically with respect to said middle plane of the machine, each of said drums having a circular cross section and being provided on its outer periphery with a plurality of equally-spaced axially-extending ribs, the displacement in height and angular displacement of said ribs being such that any plane passing through the free edges of two adjacent ribs intersects the cylindrical body of the drum, the position of the axis, the diameter and the height of the ribs of each drum being such that one of the two vertical planes tangent to the cylindrical path of the top edges of said ribs intersects the vat lying under said drum and the other of said vertical planes intersects said sloping plate merging with the upper edge of the sloping longitudinal side wall of the vat, means for rotating said drums in opposed directions to continuously draw a fabric over said drums and through the liquid in the vats, means being

provided for directing the fabric leaving each drum in the direction of the vat.

3. Machine as claimed in claim 2, wherein the means for directing the fabric leaving each drum towards the vat consists of two oppositely inclined chutes situated at opposite ends of the machine and merging downwardly into the opposite sloping walls of the vats and extending upwardly to intersect the vertical path of the fabrics leaving their respective drums.

4. Machine for washing, purging, bleaching, dyeing and like liquid treatment of webs of fabric comprising in combination a pair of vats for containing liquid, said vats being parallel to each other and symmetrically disposed with respect to the middle plane of the machine, each of said vats having a substantially horizontal bottom and a sloping longitudinal side wall rising towards the middle plane and a sloping plate merging with the upper edge of said side wall and protruding upwardly towards said middle plane, means for feeding a liquid into each vat and means for discharging and varying the level of said liquid in each vat, a first cylindrical drum and a second cylindrical drum rotatably mounted above said vats and having horizontal axes disposed in parallel and symmetrically with respect to said middle plane of the machine, each of said drums having a circular cross section and being provided on its outer periphery with a number of equally spaced axially-extending ribs, the displacement in height and angular displacements of said ribs being such that any plane passing through the free edges of two adjacent ribs intersects the cylindrical body of the drum, means for rotating said drums in opposed directions to continuously draw a fabric over said drums and through the liquid in the vats along a path comprising successive turns spaced from each other wound upon the drums and depending therefrom into the vats, means for introducing the fabric to be treated from a point above said first drum downwardly into the associated vat at a point on the side of said first drum toward which said first drum rotates when viewed from above so that said fabric will move upwardly onto said first drum at a point on the opposite side of said first drum and said fabric will follow a course of at least 360° in passing through said vat and over said first drum, said drums being positioned with respect to the associated vats to cause the fabric to be withdrawn from the baths contained in the vats onto the drums in a substantially vertical path and said means for introducing the fabric into the vat associated with the first drum being positioned to cause the fabric to be fed downwardly onto said sloping plate, means being provided for directing the fabric leaving each drum at one of its ends in the direction of the vat.

5. Machine as claimed in claim 4, wherein the means for directing the fabric web leaving each drum towards the vat situated below the other drum consists in two oppositely inclined chutes situated at opposite ends of the machine, merging downwardly into the opposite sloping walls of the vats and extending upwardly as far as to intersect the vertical path of the fabrics leaving their respective drums.

6. A machine as defined in claim 4, wherein along the upper edge of each of the sloping plates a channel-like receiver is disposed, said receivers having a common wall extending along throughout the length of said plates and a lower wall adjacent said plates, and wherein said liquid feeding means comprises a bath liquid feeding tube provided with a series of aligned openings arranged above each receiver, the bath liquid falling from said openings into said receivers and overflowing from said receivers onto the sloping plates of said vats.

7. A machine as defined in claim 4, wherein said means for discharging and varying the level of said liquid in each vat comprises a tube having a horizontal axis par-

allel with the middle plane rotatably mounted in the end walls of each vat, said tube having a cylindrical wall provided with an axially extending slot communicating with the interior of said tube, the interior of said tube having an outlet for discharging liquid entering therein, rotation of each tube causing the distance between its slot and the bottom of the associated vat to be varied, and said slot thereby determining the depth of the liquid in the vat, the liquid being deepest when said slot is furthest removed from said vat bottom.

8. A machine as defined in claim 4, wherein combs are pivotally mounted below the drums and above the vats for spacing from one another the fabric strands moving upwardly from the bath contained in the vats towards the drums.
